(57)

CLAIM

The ornamental design for a fastening device, as shown and described.

DESCRIPTION

6. Fastening device

6.1: Front/Back

6.2: Left

6.3: Perspective_back_left

6.4: Perspective_front_right

6.5: Right

6.6: Top/Bottom

The broken lines in the drawings depict portions of the fastening device that form no part of the claimed design.

1 Claim, 6 Drawing Sheets
